SAFETY WATCH ATTACHMENT

James Evans, Cody, Wyo.

Application October 1, 1947, Serial No. 777,220

1 Claim. (Cl. 24—241)

1 This invention relates to improvements in safety watch attachments.

An object of the invention is to provide an improved safety watch attachment which will provide a double right angularly disposed lock between a wrist watch and its attaching bracelet or strap.

Another object of the invention is to provide an improved double locking clip attachment for securing a bracelet or wrist encircling band or strap to the attaching eye of a wrist watch, whereby in the event that one locking device is accidentally released, the second locking device will positively hold the clip and bracelet or strap firmly connected with the wrist watch to prevent the loss of the same.

A further object of the invention is to provide a double progressively actuated locking clip for securing a bracelet or band to a wrist watch including a hinged U-shaped clamping member and a pivoted attaching arm mounted upon said clip for movement at right angles to the movement of said U-shaped clamping arm, and resilient tensioning means engageable with said attaching arm for holding the same normally in closed position.

Another object of the invention is to provide an improved double safety watch locking attachment which will be highly efficient in operation, and relatively inexpensive to manufacture and produce.

Other objects will appear as the description proceeds.

In the accompanying drawings which form a part of this application:

Figure 1 is a front elevational view of the improved safety watch attachment shown connected respectively with a wrist watch and a watch supporting bracelet or band;

Figure 2 is an elevational view of the improved safety watch attachment shown in released position connected respectively to a wrist watch and to a watch supporting bracelet or band;

Figure 3 is a sectional view taken on the line 3—3 of Figure 2; and

Figure 4 is a sectional view taken on the line 4—4 of Figure 1.

Like characters of reference are used throughout the following specification and the accompanying drawings to designate corresponding parts.

In carrying out the invention, there is provided an improved safety watch attachment including a link 1 secured to the end of a wrist encircling wrist watch supporting bracelet or band

2, and having a right angularly disposed lock 3 secured to the end of a watch supporting bracelet or band 4, the improved safety watch attachment including a safety clip 6 pivotally supported upon a transversely extending pivot pin 7 disposed transversely of the outer end of said link 1.

The improved safety clip 6 will be split at 8 on its outer end, and will be also split along one side edge thereof as at 9. Arcuate oppositely disposed seats 10 and 11 will be formed in the opposite sides of the side slot or split portion 9 of the clip 6, while the outer edges 12 and 13 disposed at the opposite sides of the end split or notch 8 in the clip 6, will be rounded and directed inwardly as at 14 and 15, for purposes hereinafter more fully described.

2 The clip 6 will be split at 8 on its outer end, and will be also split along one side edge thereof as at 9. Arcuate oppositely disposed seats 10 and 11 will be formed in the opposite sides of the side slot or split portion 9 of the clip 6, while the outer edges 12 and 13 disposed at the opposite sides of the end split or notch 8 in the clip 6, will be rounded and directed inwardly as at 14 and 15, for purposes hereinafter more fully described.

10 The clip 6 will be split at 8 on its outer end, and will be also split along one side edge thereof as at 9. Arcuate oppositely disposed seats 10 and 11 will be formed in the opposite sides of the side slot or split portion 9 of the clip 6, while the outer edges 12 and 13 disposed at the opposite sides of the end split or notch 8 in the clip 6, will be rounded and directed inwardly as at 14 and 15, for purposes hereinafter more fully described.

15 The clip 6 will be split at 8 on its outer end, and will be also split along one side edge thereof as at 9. Arcuate oppositely disposed seats 10 and 11 will be formed in the opposite sides of the side slot or split portion 9 of the clip 6, while the outer edges 12 and 13 disposed at the opposite sides of the end split or notch 8 in the clip 6, will be rounded and directed inwardly as at 14 and 15, for purposes hereinafter more fully described.

20 The clip 6 will be split at 8 on its outer end, and will be also split along one side edge thereof as at 9. Arcuate oppositely disposed seats 10 and 11 will be formed in the opposite sides of the side slot or split portion 9 of the clip 6, while the outer edges 12 and 13 disposed at the opposite sides of the end split or notch 8 in the clip 6, will be rounded and directed inwardly as at 14 and 15, for purposes hereinafter more fully described.

25 The clip 6 will be split at 8 on its outer end, and will be also split along one side edge thereof as at 9. Arcuate oppositely disposed seats 10 and 11 will be formed in the opposite sides of the side slot or split portion 9 of the clip 6, while the outer edges 12 and 13 disposed at the opposite sides of the end split or notch 8 in the clip 6, will be rounded and directed inwardly as at 14 and 15, for purposes hereinafter more fully described.

30 The clip 6 will be split at 8 on its outer end, and will be also split along one side edge thereof as at 9. Arcuate oppositely disposed seats 10 and 11 will be formed in the opposite sides of the side slot or split portion 9 of the clip 6, while the outer edges 12 and 13 disposed at the opposite sides of the end split or notch 8 in the clip 6, will be rounded and directed inwardly as at 14 and 15, for purposes hereinafter more fully described.

35 The clip 6 will be split at 8 on its outer end, and will be also split along one side edge thereof as at 9. Arcuate oppositely disposed seats 10 and 11 will be formed in the opposite sides of the side slot or split portion 9 of the clip 6, while the outer edges 12 and 13 disposed at the opposite sides of the end split or notch 8 in the clip 6, will be rounded and directed inwardly as at 14 and 15, for purposes hereinafter more fully described.

40 The clip 6 will be split at 8 on its outer end, and will be also split along one side edge thereof as at 9. Arcuate oppositely disposed seats 10 and 11 will be formed in the opposite sides of the side slot or split portion 9 of the clip 6, while the outer edges 12 and 13 disposed at the opposite sides of the end split or notch 8 in the clip 6, will be rounded and directed inwardly as at 14 and 15, for purposes hereinafter more fully described.

45 The clip 6 will be split at 8 on its outer end, and will be also split along one side edge thereof as at 9. Arcuate oppositely disposed seats 10 and 11 will be formed in the opposite sides of the side slot or split portion 9 of the clip 6, while the outer edges 12 and 13 disposed at the opposite sides of the end split or notch 8 in the clip 6, will be rounded and directed inwardly as at 14 and 15, for purposes hereinafter more fully described.

50 The clip 6 will be split at 8 on its outer end, and will be also split along one side edge thereof as at 9. Arcuate oppositely disposed seats 10 and 11 will be formed in the opposite sides of the side slot or split portion 9 of the clip 6, while the outer edges 12 and 13 disposed at the opposite sides of the end split or notch 8 in the clip 6, will be rounded and directed inwardly as at 14 and 15, for purposes hereinafter more fully described.

55 The clip 6 will be split at 8 on its outer end, and will be also split along one side edge thereof as at 9. Arcuate oppositely disposed seats 10 and 11 will be formed in the opposite sides of the side slot or split portion 9 of the clip 6, while the outer edges 12 and 13 disposed at the opposite sides of the end split or notch 8 in the clip 6, will be rounded and directed inwardly as at 14 and 15, for purposes hereinafter more fully described.

60 The clip 6 will be split at 8 on its outer end, and will be also split along one side edge thereof as at 9. Arcuate oppositely disposed seats 10 and 11 will be formed in the opposite sides of the side slot or split portion 9 of the clip 6, while the outer edges 12 and 13 disposed at the opposite sides of the end split or notch 8 in the clip 6, will be rounded and directed inwardly as at 14 and 15, for purposes hereinafter more fully described.

65 The clip 6 will be split at 8 on its outer end, and will be also split along one side edge thereof as at 9. Arcuate oppositely disposed seats 10 and 11 will be formed in the opposite sides of the side slot or split portion 9 of the clip 6, while the outer edges 12 and 13 disposed at the opposite sides of the end split or notch 8 in the clip 6, will be rounded and directed inwardly as at 14 and 15, for purposes hereinafter more fully described.

70 The clip 6 will be split at 8 on its outer end, and will be also split along one side edge thereof as at 9. Arcuate oppositely disposed seats 10 and 11 will be formed in the opposite sides of the side slot or split portion 9 of the clip 6, while the outer edges 12 and 13 disposed at the opposite sides of the end split or notch 8 in the clip 6, will be rounded and directed inwardly as at 14 and 15, for purposes hereinafter more fully described.

75 The clip 6 will be split at 8 on its outer end, and will be also split along one side edge thereof as at 9. Arcuate oppositely disposed seats 10 and 11 will be formed in the opposite sides of the side slot or split portion 9 of the clip 6, while the outer edges 12 and 13 disposed at the opposite sides of the end split or notch 8 in the clip 6, will be rounded and directed inwardly as at 14 and 15, for purposes hereinafter more fully described.

80 The clip 6 will be split at 8 on its outer end, and will be also split along one side edge thereof as at 9. Arcuate oppositely disposed seats 10 and 11 will be formed in the opposite sides of the side slot or split portion 9 of the clip 6, while the outer edges 12 and 13 disposed at the opposite sides of the end split or notch 8 in the clip 6, will be rounded and directed inwardly as at 14 and 15, for purposes hereinafter more fully described.

85 The clip 6 will be split at 8 on its outer end, and will be also split along one side edge thereof as at 9. Arcuate oppositely disposed seats 10 and 11 will be formed in the opposite sides of the side slot or split portion 9 of the clip 6, while the outer edges 12 and 13 disposed at the opposite sides of the end split or notch 8 in the clip 6, will be rounded and directed inwardly as at 14 and 15, for purposes hereinafter more fully described.

semi-circular terminal attaching hook end **17** may be inserted within the eye **21** of the wrist watch **22**, and the arcuate semi-circular terminal attaching hook end **20** pushed inwardly until its outermost end lies opposite to and engages the end of the hook end **17**. In this position, the inwardly directed opposed shoulders **14** and **15** at the opposite sides of the end slot **8** in the clip **6** will slide over the hook end **20** to resiliently tension the same and hold it in its closed position. The locking member **23** will then be moved inwardly until it snaps over the clip **6** thereby providing a double lock for the safety device which will positively prevent the same from accidentally being released from the watch in the event that the locking member **23** is swung outwardly.

While the preferred embodiment of the instant invention has been illustrated and described, it will be understood that it is not intended to limit the scope of the invention thereto as many minor changes in detail of construction may be resorted to without departure from the spirit of the invention as defined in the appended claim.

Having described the invention what is claimed as new is:

(A safety clip for attaching two articles to-

gether comprising a fixed and a pivoted arcuate semi-circular terminal hook supported by said clip, said clip being split along the outer end and along one side edge thereof for permitting said pivoted hook end to move laterally of said clip, displaceable resilient inwardly directed edges formed along the opposite sides and end of said split portion of said clip, being deformed as said pivoted hook end is moved outwardly, and a locking member adapted to overlie and encase said clip being pivotally supported thereon at right angles to the pivotal movement of said pivoted hook end.

JAMES EVANS.
